UNITED STATES PATENT OFFICE.

JOSEPH R. RITTER, OF HASTINGS, FLORIDA, ASSIGNOR TO RITTER SELF-FASTENING CONTAINERS COMPANY, OF JACKSONVILLE, FLORIDA, A CORPORATION OF FLORIDA.

BOX, CLOSURE, AND FASTENER.

1,413,994.

Specification of Letters Patent. Patented Apr. 25, 1922.

Application filed January 5, 1920. Serial No. 349,379.

To all whom it may concern:

Be it known that I, JOSEPH R. RITTER, a citizen of the United States, residing at Hastings, in the county of St. Johns, State

5 of Florida, have invented certain new and useful Improvements in Boxes, Closures, and Fasteners; and I do hereby declare the following to be a full, clear, and exact description of the invention, such as will enable others skilled in the art to which it

10 appertains to make and use the same.

This invention relates to receptacles of the knock-down type, as well as to the closures thereof and the means for fastening

15 such closures in place; and the primary object of the invention is to produce a box or crate of this kind which can be made and assembled very cheaply because its walls are exact duplicates of each other if the box

20 be a cube or are in two pairs or at most in three pairs if the box be of other shapes, and in any case the cover is made by bisecting one wall.

Another object is to produce a box of this 25 kind whose walls interengage without employing any extraneous fastening means, and whose cover when applied prevents the walls from becoming disengaged and is itself fastened very simply.

30 Another object of the invention is to produce a box of this character wherein each wall is made up of a light body as of veneer or paper board (preferably slatted, and the slats spaced if the device is to be a ventilated crate) and beads or battens across two edges of the body (or the ends of the slats) on the outer face—these battens standing along the corners of the box when set up and receiving the jars incident to rough 35 handling. As will be explained, the projecting extremities of these battens interlock at the corners of the finished structure, so that they serve a double function.

Another object of the invention is to 40 strengthen some or all of the walls by transverse re-enforcing bars, that on the cover being removable and engageable at its ends with two opposite side walls so that it serves as a locking means for the cover.

45 Another object of the invention is to pro-

vide a resilient member underlying the locking bar and overlying the cover so as to hold the latter in place under some considerable tension, thereby obviating the necessity for nails, screws, or the like.

55

One successful means for carrying out the invention is set forth below, and shown in the drawings wherein:

Figure 1 is a perspective view of this box set up and with its cover in place and 60 fastened.

Figure 2 is a transverse section through the same on the line 2—2 of Figure 1.

Figure 3 is a perspective view of the upper portion of the box with one half of the cover 65 absent and the other half being put in place.

Figure 4 is a perspective view of one wall.

By the term "wall" as herein used I refer to one of the sides or the bottom or the top 70 of a receptacle such as a box or crate. Usually there are six such walls, the lowermost being known as the bottom and the uppermost which is generally removable being known as the cover or closure, while the re-

mainder would then be side walls. If the box is an exact cube, the walls will be identical in size and construction. If it be a box which is square in one plane and longer on a line at right angles to the plane than any 75 side of the square, then there will be four walls alike in size and the remaining two like each other in size, but all six will be of the same construction. If the box be longer

one way than the other and also quite flat, 80 there will be three pairs of walls whereof those in each pair are alike in size but all are alike in construction. The only difference between the cover and any other wall is that it must be bisected as will be ex- 85 plained. Usually these receptacles are

cheap, and if they be crates they are ventilated as by being made of spaced slats. While I do not desire to be limited with respect to materials, the beads or battens may 90 be of wood and also the reenforcing bars, and the fillers of metal or other material, such as veneer or paper board tacked or otherwise secured across the inner faces of the other parts. This filler may be in strips 95

100

or slats slightly spaced from each other at their inner edges, although it is possible to produce ventilation by other means not necessary to amplify. In the wall constituting the cover the battens are sawed through, preferably at their midlength, so that they are divided or made sectional, and of course no reenforcing bar of the cover is tacked to the filler. It will be obvious that the machinery of a mill can be so set as to produce box walls of this kind in great numbers and in standard sizes; and, as the process of interlocking them later is a simple one, cheap labor can be employed so that the total cost of production is minimized. Or, a shipment of walls flattened out and packed very closely could be made, leaving the purchaser to set up the boxes as he needs them for use. Finally, after a box has made its outgoing trip, the consignee removes the contents and knocks down or collapses the box so that it can be returned in small space for reuse.

Referring first to Figure 4, the wall herein shown is made up of two slats 1 slightly spaced at their adjacent inner edges as at 2, and held in proper relative position by means of two beads 3 secured across their ends on their outer faces. These beads may be formed in any appropriate manner and of any proper material, and they may well be wooden strips or battens to which the slats are tacked from the inner side. The ends of the beads project at 4 beyond the side edges 5 of the two parts or slats of the wall here shown. Secured also across their outer faces and at about their midlength is a reenforcing bar 6, its ends 7 in this instance projecting as do the ends 4 of the beads. In setting up a box whose walls are so made, the four sides are stood on edge, two of them with the slats upright and the other two with the slats horizontal, and the projecting ends 4 of the beads are interengaged with each other in the manner best seen in Figure 1. This holds the sides to each other, and the interengagement of the projecting ends of the beads on the bottom wall as shown at 4' also holds this in place. Manifestly the top could not now be inserted and its projecting ends interengaged in the same way if it were in one rigid piece, and therefore its beads or battens are divided where desired, preferably bisected as indicated at 8, on a line opposite the space between its slats.

Figure 3 illustrates the manner of applying the cover or closure to the box so set up. In this view one section is shown as just being put in place, having been moved in the direction of the arrow until the projecting ends 4" of its bead sections 3" have passed under the projecting ends 4 of the bead 3 on the left wall. The contact of the outer edge 5 of its slat 1 with the inner faces of the slats of said left wall will limit the movement of this section of the cover to the

left, and then its inner edge is borne down until its slat strikes the upper edge of the uppermost slat 1' of the wall in the foreground and the corresponding slat 1" of the further wall. These might be called end walls, because they underlie the ends of the slat in the top. The other section of the top can now be brought into place and moved to the right in a similar manner as will be understood, and finally borne down until the cover appears as seen in Figure 1 and the inner ends of the sectional beads abut as indicated at 8. This spreads the cover until its outer edges hold the side walls apart and prevent their falling inward, while its beads engage those of the end walls and prevent them from falling outward. The upper projecting ends 7 of the reenforcing bars 6 on the end walls will lie behind the abutting ends of the sectional beads on the cover.

The cover fastener is by preference in two members. One of these is the reenforcing bar 6 of the cover itself, which bar will have its ends rabbeted as indicated at 6' in Figure 2. This bar may be laid across the midlength of the cover on the outer faces of its slats, and its rabbeted ends engage in the openings 2 between the slats of the side walls, under their uppermost beads. But I prefer also to use another member which as shown in Figures 1 and 2 is a strip 9 of veneer or some other flexible and considerably resilient material. This strip underlies the first member or bar 6 with its ends overlying the abutting ends of the bead sections. When this strip is employed, it is applied first and obviously its center will not then be depressed into contact with the slats of the cover. The fastening element or bar 6 is applied later, its center depressing the center of the strip until it contacts with the slats of the cover, and thereby causing the ends of the strip to bear down with considerable tension on the inner portions of the bisected beads of said cover to hold latter firmly in place; and the rabbets at the ends of the fastening bar prevent its dislodgment while the resiliency of the strip holds this bar normally in such position as to retain the rabbets in their engagement with the beads of the side walls. Obviously the fastening member 9 could be replaced by some other expansive or resilient element, or the fastening member 6 could be modified in structure or it might be used without the strip 9. Also if the sides be solid instead of slatted as shown, they may be provided with openings near their upper edges in place of the spaces 2, or some other means for fastening the ends of the bar 6 to the side walls may be employed. The strip extends longitudinally of the cover and overlies its space 2 so as to practically close the same, and therefore this member may be em-

ployed where the walls are solid or are not ventilated. Figure 2 shows the fastening bar so rabbeted that when inserted over the strip 9 the latter springs the inner portions 5 of the slats 1 downward, and the structure is such that the cover fastener will hardly become dislodged even if the device be subjected to rough usage.

I have spoken of the bar 6 and illustrated 10 but one such bar across each side and across the cover, but if any element or elements of this box are of such size that it is thought desirable to use more than one such bar, it may obviously be done without departing 15 from the spirit of the invention. Also I have shown and described the sides and the cover as made up of but two strips or slats, and here again the size of any element may be such that the filler should be in more than 20 two pieces, although they will be spaced from each other at their inner edges if ventilation is desired; and each of such spaces may be covered with a strip such as that numbered 9 herein.

25 What is claimed as new is:

1. A box closure comprising a cover made up of two abutting sections whose outer edges are adapted to engage inside two opposite walls of the box and whose ends are

30 adapted to overlie the other walls thereof, and a fastening element crossing the sections and adapted to engage the first named walls.

2. A box closure comprising a cover made up of parts whose outer edges are adapted 35 to engage inside two opposite walls of the box and whose ends are adapted to overlie other walls thereof, and depending beads across the ends of said parts adapted to contact on the outer sides of the other two 40 opposite walls; combined with fastening means overlying the cover and adapted to engage the first mentioned two opposite walls of the box.

3. A box closure comprising a cover made 45 up of sections whose outer edges are adapted to engage opposite walls of the box and whose ends are adapted to engage other walls thereof, a strip overlying andlapping the inner edges of said sections, and a fastening element crossing the strip and adapted to engage the first named walls.

4. A box closure comprising a cover made up of parts whose outer edges are adapted 55 to engage opposite walls of the box and whose ends are adapted to engage other walls thereof, and beads across both ends of each part; combined with a strip overlying the inner edges of said parts and the inner ends of their beads, and a fastening 60 element crossing the strip and adapted to engage the first named walls.

5. A box closure comprising a cover made up of two parts whose outer edges are adapted 65 to lie inside two opposite walls of the box and whose ends are adapted to overlie two

other walls thereof, and beads across both ends of each part; combined with a strip overlying the inner edges of said parts and the abutting ends of their beads, and a fastening bar overlying the strip and adapted 70 to be engaged at its ends with the two of said walls.

6. A box closure comprising a cover made up of parts whose inner edges are adjacent and whose outer edges are adapted to stand 75 in contact with opposite walls of the box, and beads at the ends of each part on its outer face; combined with a resilient strip overlying said adjacent edges and beads, and a fastening bar crossing the strip and 80 adapted to be engaged with said walls at points to spring the strip into contact with said parts.

7. The combination with a box having 85 beads on two opposite side walls near their upper edges; of a cover disposed between said walls and engaging the remaining side walls, and a fastening member extending across the cover and having its ends engaged under said beads, and a resilient member 90 held under said fastening member and bearing on said cover.

8. The combination with a rectangular receptacle having openings in two opposite side walls near their upper edges; of a cover 95 disposed between said walls and engaging the remaining side walls, and a fastening bar separable from the cover and extending across the cover and having rabbeted ends entering said openings and extending outward past said first mentioned side walls. 100

9. The combination with a box having 105 openings in two opposite side walls near their upper edges; of a two part cover disposed between said walls and over the remaining side walls, a strip overlying the adjacent edges of the parts of said cover, and a fastening bar crossing the strip and cover and engaging said openings.

10. The combination with a box having 110 openings in two opposite side walls near their upper edges; of a sectional cover disposed between said walls and over the remaining side walls, a bar crossing the cover and having its ends removably engaging 115 said openings, and a resilient element between the bar and cover for holding its parts in place.

11. The combination with a box whereof 120 each wall is composed of slats spaced at their adjacent edges and transverse beads across the ends of the slats on their outer faces, one wall constituting a cover and its beads being formed in abutting sections, the outer edges of the cover slats abutting the 125 side walls of the box and their ends overlying the end walls of the box and underlying the abutting sections of said beads; of a strip whose ends overlie said beads where they abut, and a fastening element crossing 130

said strip with its ends extending between the slats of said side walls and engaged beneath their beads.

12. A knock-down box made up of walls 5 whereof each has beads along two opposite edges projecting at both ends beyond the remaining edges, the projecting portion of each bead directly contacting with the projecting portions of beads on two other walls 10 at a corner of the box, one wall constituting the cover and being made in sections; combined with fastening means overlying the cover and adapted to engage other walls of the box.
13. A knock-down receptacle made up of 15 six walls, each having its side edges abutting two walls and its ends extending over two other walls, and battens across the outer faces of said ends and projecting beyond 20 said edges, the projecting portion of each batten engaging two other battens at a corner of the receptacle, one wall constituting the cover and being bisected and its battens

formed in abutting sections; combined with fastening means for holding the sections of 25 each batten alined and the cover in place.

14. A knock-down box made up of similar walls, each composed of slats having their inner edges spaced, battens fixed across their ends and projecting beyond their outer 30 edges, and a reenforcing bar fixed across the slats parallel with said battens, one wall constituting the box cover having its battens divided and its bar removable, the projecting portion of each batten detachably engaging 35 the projecing portions of the battens on two other walls at a corner of the box; combined with means for fastening said removable bar over the cover to hold the latter in place.

In testimony whereof, I affix my signature, in the presence of two witnesses.

JOSEPH R. RITTER.
